UNITED STATES PATENT OFFICE

LOUIS SIMMIONS, OF NEW YORK, N. Y.

VOCALSCOPE

Application filed March 21, 1930. Serial No. 437,902.

This invention relates to a vocalscope, a meter for measuring the quality of one's voice.

The invention has for an object the provision of a device of the class mentioned which is of simple durable construction, dependable in use and efficient in action, and which can be manufactured and sold at a reasonable cost.

10 A microphone shows more than ever the sins of the speaking voice for the faulty, throaty, nasal production is magnified a thousand folds. No one can hear fully their own voices, in speech nor in song. For this reason I have evolved an electrical instrument with which one can magnify the sound in the inner ear so one can hear correct his or her own faults. The faults particularly referred to are those in intonation and faults in modulation, in speech and in song.

In other words, one can hear his or her own voice as others hear it. It is the low ventricular sound that one cannot hear, and it is in these fundamentals of the melodic line that all the damage is done by a teacher. Most singers and speakers control the sound of their voices as they hear it themselves, instead of projecting their voices as others hear it so they miss the inner quality or basic sound that is called continuant in microphonic work of the radio and sound films, now a real field worth while.

The principal purpose of the meter is so indicated in the middle sector when the voice is tuned to resonance. It will indicate the pressure of the breath necessary for the vowel continuant. It will indicate in the magnetic field of the meter the correct tone production in the active and inactive notes in the scale. It will show the student that he can check up the quality, resonance, pitch and right power of his voice by the ear phone so that he does not have to depend all the time on his teacher. He will hear his voice as others hear it. Once he can hear his own voice, it will cure him forever of trying to sing or speak with a voice he does not possess. And by controlling the pressure and resistance it will bring him to the understanding of his own voice.

50 For further comprehension of the inven-

tion, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a front elevational view of a device constructed according to this invention.

Fig. 2 is a side elevational view of Fig. 1.

Fig. 3 is a horizontal sectional view taken on the line 3—3 of Fig. 1.

Fig. 4 is a fragmentary sectional view taken on the line 4—4 of Fig. 2.

Fig. 5 is a fragmentary view similar to Fig. 1, but illustrating another arrangement.

Fig. 6 is a schematic wiring diagram of the various parts shown in Figs. 1 to 4.

Fig. 7 is a side elevational view of a device constructed according to another embodiment of the invention.

Fig. 8 is a fragmentary horizontal sectional view looking in the direction of the line 8—8 of Fig. 7.

Fig. 9 is a sectional view looking in the direction of the line 9—9 of Fig. 7.

Fig. 10 is a perspective view of Fig. 7.

Fig. 11 is a schematic wiring diagram of the various electrical parts shown in Figs. 7 to 10.

Fig. 12 is an enlarged detailed view of a portion of Fig. 1 and Fig. 10 showing an indicator in another position.

In Figs. 1 to 6 inclusive, a container 10 has been illustrated formed with a front panel board 11. This container is arranged in a position so that the board is substantially vertical. Doors 12 are hingedly mounted on the sides of the container and are adapted to enclose the panel board 11. One of the doors is formed with a cutout portion 13 for receiving an ear phone. A base element 14 is attached upon the bottom of the panel so that it may rest upon a flat surface. A handle 15 is mounted upon the top of the container to permit manual carrying from place to place.

A very sensitive galvanometer 16 is mounted upon the panel board so that its face may

be read from the outside and electrical connections add to it from the interior of the container. A horn 17 is also mounted upon the panel board 11 directly to the front of a transmitter 18 mounted upon a sound board 19 supported within the container 10. A jack 20 for receiving a plug connected with ear phones, a switch 21 and a rheostat 22 are held mounted upon the panel board 11.

Fig. 5 distinguishes from Fig. 1 only in the arrangement of the parts upon the panel board. The galvanometer is shown arranged on the bottom and the horn and microphone at the top. This is only for indicating that different arrangements may be had to best suit any particular pupil. A means is also provided upon the panel board 11 for indicating certain positions of the pointer of a galvanometer. This means consists of one or more flexible pointer arrangements. Each of these pointer arrangements consists of a plurality of links 23 pivotally connected to each other at their ends so as to be in one continuous line. The innermost link, indicated by reference numeral 23', is pivotally mounted on a post 24 projecting from the panel 11. The outermost link, indicated by numeral 23'', is formed with a pointer portion 25. The front ends of alternate links are provided with eye elements 26, and a flexible cord 27 is attached upon the front end of the link 23'' and passed thru each of these eyelets and thru an aperture in the post 24, and terminates in a sling 28. The frictional connection between the various links should be great so that they maintain any positions in which they are manually placed.

During the operation of the device, when the pointer of the galvanometer moves across certain divisions upon this scale, the indicating means may be set for indicating the position so that upon subsequent trials the old position may be kept in mind. Upon conclusion, the indicator means may be contracted into a small compass by drawing upon the sling 28 so that the various links assume adjacent positions as shown in Figs. 1 and 10.

The various electrical instruments shown in Figs. 1 to 5 inclusive are connected in series as indicated in Fig. 6. In operation of the device, the rheostat 22 should be adjusted so as to get a convenient fluctuation of the indicator of the galvanometer 16. If the pupil wants to, he may use a pair of ear phones by merely plugging them into the plug 20. It is advisable that he next pronounces the various vowels and then vowels connected with certain consonants, and watches the fluctuations of the galvanometer pointer. In this manner he may be properly taught about the resonance of his voice. In addition, the ear phones permit him to listen to his voice as other people hear it, which is slightly different to the way he himself hears it.

In the modified form of the device illustrated in Figs. 7 to 11 inclusive, a container 30 has been illustrated arranged with a panel 11. This container is so positioned that the panel is horizontal. A cover 31 is hingedly mounted upon the top of the container and is arranged to assume an inclined position as shown in Fig. 7, by reason of a chain 32 limiting its pivoting to this position only. Latch elements 33 are arranged upon the cover and the container so that the container may be locked closed. A handle 34 is fixed upon one side of the container to permit manual moving from place to place.

A transmitter 35 is mounted upon the cover 31 and also supports a horn 36. This transmitter is wired up in series as indicated in Fig. 11 with an ear phone 37, a plurality of rheostats 38, switches 39 and a galvanometer 40. In all, three rheostats have been illustrated, preferably they should be arranged in one straight line along the panel. The ear phone is also shown provided with a switch 41 so that it may be cut out of the circuit at will. When this is done, a switch 43 must be shunted across the open circuit left by the operation of the switch 41. An inspection of the drawings clearly indicates the wiring and for this reason a detail tracing of the current is not thought necessary. A means is also provided upon the panel 11 for indicating certain positions of the pointer of the galvanometer. This means is shown in detail in Fig. 12 and has been fully described before in this specification.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A meter for measuring the quality of the voice, comprising a container with a panel board, a galvanometer mounted upon said container, and a transmitter supported upon the panel board and connected in series with a rheostat, a switch, a source of current and the said galvanometer.

2. A meter for measuring the quality of the voice, comprising a container with a panel board, a galvanometer mounted upon said container, and a transmitter supported upon the panel board and connected in series with a rheostat, a switch, a source of current and the said galvanometer, said transmitter being mounted upon a sound board arranged within the container.

3. In a meter for measuring the quality of the voice, a container with a panel board, a galvanometer mounted upon said container, and means for indicating certain positions

of the pointer of the galvanometer, said means comprising a plurality of links pivotally connected with each other, the rear link being pivotally mounted upon a post, a front link being provided with a pointer, and the front ends of alternate links being provided with eye elements receiving a string attached to the first link and passing thru an aperture formed in the said post.

10 4. In a device of the class described, a panel board, a galvanometer mounted upon said panel board, a post projecting from the panel board, the innermost link of a plurality of links pivotally connected to each other at 15 their ends so as to be in one continuous line and pivotally mounted upon said post, the outermost link of said plurality of links formed with a pointer eye, elements attached to the front ends of alternate links, and a 20 flexible cord attached upon said outermost link and passing through said eye elements and through an aperture formed in the said post.

5. In a device of the class described, a panel 25 board, a galvanometer mounted upon said panel board, a post projecting from the panel board, the innermost link of a plurality of links pivotally connected to each other at their ends so as to be in one continuous line 30 and pivotally mounted upon said post, the outermost link of said plurality of links formed with a pointer eye, elements attached to the front ends of alternate links, and a flexible cord attached upon said outermost 35 link and passing through said eye elements and through an aperture formed in the said post, said flexible cord terminating in a sling.

6. In a meter for measuring the quality of the voice, a container with a panel board, a 40 galvanometer mounted upon said container, and means for indicating certain positions of the pointer of the galvanometer, said means comprising a plurality of links pivotally connected with each other, the rear link being 45 pivotally mounted upon a post, a front link being provided with a pointer, and the front ends of alternate links being provided with eye elements receiving a string attached to the first link and passing thru an aperture 50 formed in the said post, said pivotal connection between the links having sufficient friction so as to maintain any positions in which they are manually placed.

In testimony whereof I have affixed my 55 signature.

LOUIS SIMMIIONS.
